UNITED STATES PATENT OFFICE

2,476,857

EXPANSION CHAMBER

Louis N. Grafinger, Sharon, Pa., assignor to Westinghouse Electric Corporation, East Pittsburgh, Pa., a corporation of Pennsylvania

Application March 8, 1946, Serial No. 653,187

2 Claims. (Cl. 60—44)

1

This invention relates generally to starting devices, and more particularly to devices of this type which are suitable for accelerating a load unit to a relatively high speed in a relatively short period of time.

The Government of the United States has been granted a certain royalty-free license for governmental purposes with respect to the invention disclosed herein.

This invention is specifically adapted for starting free spinning gyroscopes of the type utilized in the directional control of torpedoes. However, it will be apparent to one skilled in the art that this invention has general application and may be utilized in the starting of a wide variety of load units, for example, the starting gear of internal combustion engines.

In certain of its aspects this invention is related to a copending application of L. B. Lynn, Serial No. 653,186, entitled Control devices, filed on the same date as this application, and assigned to the same assignee as this invention.

In certain other of its aspects this invention is related to a copending application of L. D. Jennings, Serial No. 653,190, entitled Cartridge starting mechanism, filed on the same date as this application and assigned to the same assignee as this invention.

In the operation of torpedoes for directional control purposes, it has been found satisfactory to employ gyroscopes of the free spinning type, that is, gyroscopes which are brought up to a fairly high speed prior to the time of launching of the torpedo and then permitted to spin free for the duration of the torpedo's run. Such a run is of sufficiently short duration both for test or exercise and war shot purposes that the gyroscope does not decelerate sufficiently or to a point where it no longer functions effectively as a directional control device.

The starting requirements for a gyroscope of the type generally described are rather severe. With modern electrically operated torpedoes the practice is to insert the torpedo in the torpedo or launching tube and then to apply the air pressure source to the tube to eject the torpedo therefrom. Usually about one-half of a second is required for the torpedo to move from the launching tube. In that interval the torpedo is accelerated to approximately full speed. During this interval such preliminary operations as bringing the directional control gyroscope up to speed, must be accomplished. Otherwise the torpedo will be inadequately controlled after launching.

2

Numerous devices for starting torpedo gyroscopes have been considered and experimented with. One form which proved successful and could be cheaply manufactured involved a small electric motor energized upon closure of the torpedo's trigger switch the instant torpedo movement from the launching tube began. These motors were designed for short life, since their useful purpose was fulfilled in a matter of less than one-half of a second after operation began. In this brief interval the motor accelerated a two pound 3½ inch diameter gyro wheel to a speed of about 12,000 R. P. M.

There are applications in torpedoes, for example those involving a primary battery as the main source of propulsion energy for the torpedo wherein it is not always convenient to provide sufficient secondary battery energy to drive the gyroscope motor prior to launching. The use of compressed air and suitable mechanical coupling offers a solution to the problem but has the attendant disadvantage of the space required for an air reservoir together with other equipment for controlling the air supply. Rather than this, the use of a cartridge as the energy source for starting the gyroscope appears to offer the more sensible solution.

However, a very definite problem is involved in the use of a cartridge as the energy source due to the high rate at which gas pressure is built up. In early experimenting with cartridge starting devices in which the products of combustion of the cartridge were applied to a turbine connected to a gyroscope, it was found that the accelerating torques were so high that torsional shearing of the shaft connecting the turbine and load unit frequently occurred. In other cases when the shaft carried the load without failure, it was found that while the initial acceleration was extremely high the available energy was so inefficiently utilized that acceleration to full speed of the load unit was not obtained.

This condition was overcome in part by utilizing cartridges in which slower burning powders were employed and also by graduating the powder pellet sizes along the length of the cartridge to additionally control the combustion. Further improvements were realized by the addition of suitable screens between the cartridge and the exhaust port in the cartridge chamber to prevent the ejection of partially burned pellets from the cartridge chamber, as described in the mentioned copending application of L. D. Jennings, Serial No. 653,190. The screens thus confine combustion and, hence, gas pressure

build up to the cartridge chamber which increases the overall efficiency.

While the foregoing expedients measurably improve the operating characteristics, the acceleration obtained is yet measurably higher than is required for most applications. Better overall results can be obtained by reducing the peak pressure and the rate of build up of pressure and to increase the duration of the pressure, which through the turbine has the effect of supplying to the load unit a reduced torque of greater duration.

Accordingly, a principal object of this invention is to provide an impulse starter mechanism of the class described in which optimum accelerating characteristics for a particular load unit are obtainable.

Another object of this invention is to provide an impulse starter mechanism of the class described embodying a cartridge as the energy source in which the products of combustion of the cartridge are controlled to provide a satisfactory pressure-time characteristic.

A further object of this invention is to provide an impulse starter of the type referred to in which the available energy produced by detonation of a cartridge is efficiently utilized.

Further separate and combined objects of this invention are to provide an impulse starter mechanism, utilizing a cartridge as the energy source, which is compact and light in weight in relation to power developed, which is simple in mechanical detail and cheaply and easily manufactured, which requires a minimum of maintenance effort and which rapidly and uniformly accelerates a load unit coupled thereto with a minimum of mechanical shock.

The foregoing statements are merely illustrative of the various aims and advantages of this invention. Other objects and advantages will become apparent upon a study of the following specification when considered in conjunction with the accompanying drawings, in which:

Figure 1 illustrates an assembly partly in section of an impulse starter mechanism embodying the principles of this invention.

Fig. 2 is a modification of the invention illustrated in Fig. 1, and

Fig. 3 is another view of the invention illustrated in Fig. 2 showing the turbine and associated declutching mechanism in longitudinal section.

Referring now to Fig. 1 of the drawings, numeral 1 designates the cartridge firing device and numeral 2 denotes the turbine mechanism.

The cartridge firing device includes a block 3 which may be of bar stock having formed therein a cartridge chamber 4 for receiving a cartridge 5. The breech end of the block 3 is so designed that the cartridge may be inserted directly into the cartridge chamber. At the end of block 3 opposite the breech end thereof, an opening 6 is provided of smaller diameter than the cartridge chamber, thus providing a shoulder against which screen 7 may bear. The length of the cartridge chamber is such as to accommodate the cartridge 5 and screen 7 as illustrated. The breech end of block 3 is sealed by means of the breech block 9 which threads over the threaded section of block 3 and clamps the cartridge rim therebetween. Several types of cartridges are available. The type here illustrated is equipped with two detonating cannon caps connected in parallel circuit relation across leads 13 and 15, which pass from the cartridge through a hole

in the breech block 9. The cannon caps are highly sensitive and are readily detonated by a small impulse of electrical energy, for example, that obtainable from a small permanent magnet impulse generator.

It has been found in using cartridges as the energy sources in impulse starting devices that if no means is provided for effecting complete combustion of the cartridge powder in the cartridge chamber, the efficiency of the system may be at a relatively low level, since the available energy is not completely utilized. The provision of the screen 7 obviates the possibility of unburned or partially burned powder pellets escaping from the cartridge chamber but yet affords ready passage of gases therefrom. Thus complete combustion of the powder takes place in the cartridge chamber causing effective application of gas pressure to the turbine and additionally maintaining a high pressure and temperature in the cartridge chamber, both of which are essential to complete combustion.

The turbine is composed of a pair of circular end plates 25 and 26 (see also Fig. 3) between which are placed and secured at equal peripheral distances the nozzle blocks 27. Bearing supports 28 and 29 are respectively secured centrally of the end plates 25 and 26, bearing support 28 being provided with a concentric insert 30 having a peripheral groove 31, the assembly forming an annular passage 32. Each of the nozzles 27 communicates with the annular passage 32 through tubes 33 and the cartridge chamber 4 is connected with the annular passage by the threaded tubular section 34. One end of the turbine shaft 35 is housed in a bearing 36 secured in concentric insert 30, while the shaft portion on the opposite side of turbine rotor 37 is carried in a bearing 38. A threaded extension 39 of the turbine shaft, extending through the bearing housing 29 is journaled in a bearing 40 in the extreme end of the housing 29. A nut 41 is threaded over the threaded shaft section 39 and is keyed against rotational movement in the axial grooves 42 formed internally of bearing housing 29. Turbine shaft 35 is biased to the right as viewed by the spring and plunger assembly 43. One element 44 of a clutch assembly 45 is keyed to the extremity of shaft extension 39. Clutch element 46 is connected to a shaft 47 which is connected to a load unit (not shown), for example, the directional control gyroscope of a torpedo.

The blades or buckets 50 of the turbine 37 are milled about the periphery of a blank having the cross sectional configuration seen in Fig. 3.

The device thus far described is operable as hereinbefore noted. However, measurable improvements are achievable by the addition of the expansion chamber 52 which threads into the block 3 and communicates with the opening 6 between the cartridge chamber and turbine through the orifice 53. The purpose of the expansion chamber is to convert what would be a large torque of very short duration to a smaller torque of longer duration.

When the cartridge is fired, the high pressure gas is applied to the turbine. Some of this gas bleeds off through the orifice into the expansion chamber. The gas impinging on the turbine 70 blades drives the turbine in rotation and the load attached thereto is accelerated. Simultaneously therewith nut 41 travels along threaded section 39. Bleeding off of the gas continues until the gas pressure peak is reached and then begins to fall. The pressure differential reverses

and the high pressure gas in the expansion chamber is supplied to the turbine tending to maintain the pressure. The total effect of the expansion chamber is thus to reduce the peak pressure and the rate of build up of the pressure and to increase the duration of the gas pressure. Since the turbine torque is a function of the gas pressure, the accelerating torques applied to the load unit are thus relatively uniform and mechanical shock as a consequence is minimized. When nut 41 reaches the limit of its axial travel, the turbine shaft which is yet rotating is moved axially to the left against the bias of spring and plunger assembly 43 disconnecting the turbines from the load unit at clutch 45.

In Figs. 2 and 3, the expansion chamber 52a is arranged as a shell about the cartridge chamber. It is reinforced by a metal band 55 arranged centrally thereof and is in communication with the cartridge chamber through a plurality of radially disposed holes 56. The function here is the same as that of the invention illustrated in Fig. 1; hence, a further discussion thereof is deemed unnecessary. The advantage of this embodiment resides primarily in the compactness of the structure provided.

The foregoing disclosure and the showings made in the drawing are merely illustrative of the principles of this invention and are not to be interpreted in a limiting sense. The only limitations are to be determined from the scope of the appended claims.

I claim as my invention:

1. Apparatus for controlling the gas pressure resulting from detonation of a cartridge in a cartridge chamber comprising, in combination, a block having a cartridge chamber formed therein

and an orifice therethrough communicating with said cartridge chamber, screen means arranged in said block between said orifice and said cartridge chamber, said block having a plurality of holes therethrough communicating with said orifice, and a casing of larger cross sectional dimension than said block and having the extremities thereof flanged inwardly against said block and sealed thereto in position straddling said holes to form a chamber about said block.

5 2. In combination, a member of circular cross section having a cartridge chamber formed therein and an orifice extending through the end thereof in communication with said cartridge chamber, said block further having a plurality of radially disposed holes therethrough communicating with said orifice, a metal housing concentrically arranged in spaced relation about said member and straddling said radially disposed holes, and means sealing the extremities of said metal housing to said block so that said orifice communicates with the chamber formed by said housing about said member through said radially disposed holes.

10 15 20 25 LOUIS N. GRAFINGER.
